UNITED STATES PATENT OFFICE.

BROR J. LINDGREN, OF BUFFALO, NEW YORK, ASSIGNOR TO NIAGARA MACHINE & TOOL WORKS, OF BUFFALO, NEW YORK, A CORPORATION OF NEW YORK.

SIDE-SEAMING PRESS.

Application filed April 4, 1927. Serial No. 180,652.

This invention relates to a side seaming press which is more particularly adapted for side seaming sheet metal cones which are made from a flat metal blank, although the 5 same may also be designed for side seaming sheet metal tubes of cylindrical form.

It is the purpose of this invention to provide a machine of this character whereby the operation of forming the hooks on the 10 opposing longitudinal edges of the tubular blank and the operation of interlocking said hooks and seaming them may be performed easily, expeditiously, and with a minimum expenditure of power and thereby effecting 15 a considerable economy in the cost of doing such work.

In the accompanying drawings:

Figure 1 is a perspective view of a portion of a press equipped with my invention. 20 Figure 2 is a top plan view of the lower dies and adjacent parts of the means whereby the hooks are formed on the sheet metal blank, this view being taken on line 2-3, Fig. 1, looking downwardly. Figure 3 is 25 a bottom plan view of the upper dies and adjacent parts of the means for forming said hooks, the view being taken on line 2-3 looking upwardly. Figure 4 is a vertical transverse section taken on line 4-4, Fig. 30 8, showing both the hook forming and seaming mechanism in an open position, and the blank in position for forming hooks thereon. Figure 5 is a similar view showing the press closed and the hooks formed on the opposite 35 longitudinal edges of the tubular blank. Figure 6 is a similar view showing the press open and the hooks of the tubular blank loosely interlocked preparatory to seaming the same. Figure 7 is a similar view showing 40 the press closed and the interlocked hooks of the tubular blank seamed together. Figure 8 is a vertical longitudinal section of the press taken on line 8-8, Fig. 4, and showing the hook forming and seaming dies 45 in an open position. Figure 9 is a fragmentary vertical longitudinal section taken on line 9-9, Fig. 2. Figure 10 is a plan view of the sheet metal blank from which the cone is made. Figures 11, 12, and 13 50 are perspective views representing the different stages of the operations performed on the blank for completing the form of the same.

In the following description similar characters of reference indicate like parts in the

several figures of the drawings. The sheet metal blank shown in Fig. 10 is an example of one adapted to be operated upon for producing a conical metal tube. This blank has the form of a circular disk 20 which is somewhat more than half a circle in circumference and provided with a curved inner edge 21 of small diameter, a curved outer edge 22 of large diameter, and two radial or longitudinal edges 23, 24 connecting corresponding ends of the inner and outer edges of the disk so that the same approximates the form of a crescent. This blank is first bent by a bending or rolling machine in any approved manner so that the same forms a cone which is open at opposite ends and the longitudinal edges of the blank lap one over the other, as shown in Fig. 11. The conical blank is now placed in the present press and parts of the mechanism operate to form 60 an outstanding flange or hook 25 on the longitudinal edge 23 of the blank and an instanding flange or hook 26 on the other longitudinal edge 24 of the same, as shown in Fig. 12. The blank is then removed from 65 the hook forming mechanism and placed in the seaming mechanism of the press whereby the flanges or hooks are caused to interlock with each other and become seamed together and thereby complete the conical 70 tube, as shown at 19 in Fig. 13.

The press whereby these hook forming and seaming operations are performed in accordance with my invention is preferably constructed as follows:

The numeral 27 represents the main frame of the press upon the lower part 28 of which some of the working mechanism is mounted and upon the upper part of which is guided a vertically movable plunger or slide 29 carrying other members of the working mechanism, these elements of the press being of usual and well known construction. Projecting forwardly from the lower part 28 of the main frame is a horn or arm 30 which tapers forwardly and has a horizontal upper side and an inclined underside. The horn is provided at the rear end with a cylindrical horizontal shank 31 which is seated in a correspondingly shaped socket 32 in the main frame and is capable of longitudinal adjustment and also turning therein for accurately adapting the parts on the horn for cooperation with the other parts of the machine. For this purpose the horn is pro- 100 105 110

vided on its opposite sides with shoulders 33 adapted to engage either directly with the front side of the frame, as shown in Fig. 2, or against shims or fillers placed between their shoulders and the front side of the frame, and a clamping screw 34 connected with the rear end of the shank 31 and bearing with its head against a cross piece 35 bearing against the rear end of the socket, as shown in Fig. 8. By turning the shank in the socket and adjusting the horn lengthwise therein the horn can be shifted circumferentially and longitudinally for bringing the parts mounted thereon into the desired position relative to other working parts of the press.

On its upper side the horn is provided with means for engaging the inner side of the interlocked flanges or hooks of the blank and seaming the same in co-operation with other parts. In the preferred form of these inner or lower seaming means the same consist of a lower longitudinal flattening block 36 which is seated in a rabbet 37 in the upper side of the horn and has its upper side flush therewith. This block may be held in place by one or more screws 38 connecting the same with the horn. Adjacent to one side of the lower flattening block, preferably the right side thereof, the horn has a longitudinal groove 39 which extends underneath this block and in this groove is arranged a vertically movable gage 40 having the form of a bar which is yieldingly held in its elevated position by one or more springs 41 arranged between the underside of this gage and pockets 42 in the bottom of the gage groove, as shown in Figs. 4-8. In its operative position the gage projects with its upper edge above the lower flattening block, as shown in Fig. 4, and its movement in this direction under the action of the springs 41 is limited by a shoulder 43 on the gage striking the underside of the lower flattening block, as shown in Fig. 4.

Movable toward and from the upper side of the horn is an intermediate bracket or carrier 44 which carries means adapted to co-operate with those on the horn for flattening and seaming the interlocked hooks of the blank and also means forming part of the mechanism for producing hooks on the blank. This bracket is movable vertically and for this purpose is preferably guided by means of two vertical guide bars 45 projecting downwardly from opposite corners of the rear end of the bracket and engaging with guide grooves or ways 46 arranged on opposite sides of the rear part of the horn. This bracket is yieldingly held in its elevated inoperative position by one or more springs 47 bearing at their lower ends against the upper side of the horn and at their upper ends against a lifting bar 48 secured crosswise to the rear part of the

bracket or carrier. The upward movement of the bracket or carrier under the action of the springs 47 is limited by a stop bar 49 secured crosswise to the lower ends of the guide bars 45 and adapted to engage the underside of the horn, as shown in Fig. 4.

On its underside the carrier 44 is provided with a longitudinal groove 50 in which is secured, by screws 51, an upper flattening block 52 which has a longitudinal groove 53 adapted to receive the interengaging edge portions of the blank and co-operate with the tool on the horn for seaming and flattening the joint or seam between the edges of the blank.

On the upper side of the carrier are mounted two lower die holders 54, 55, forming part of the means for producing hooks on the longitudinal edges of the blank. Each of these lower die holders is pivoted at its front end to the carrier by a vertical screw 56 which enables these die holders to be turned horizontally into different angular positions relative to each other for seaming cone shaped tubes of different angularity. For this purpose the carrier is provided at its rear end with two rows of adjusting openings 57, each row being concentric with one of the pivot screws 56 and one another being adapted to receive a clamping screw 58 on the rear end of the respective lower die holder to fasten the same in its working position.

On its upper side the lower left die holder is provided with a longitudinal groove 59 which receives a lower left hook die 60 forming part of the means for producing the upstanding hook or flange 25 on the blank and a gage 61 which is somewhat higher than the die and arranged between the die 60 and the right wall of the groove 59, said die and gage being held in this groove by one or more set screws 62 arranged on the inner part of this holder. On its upper side the lower right die holder is provided with a longitudinal groove 63 the left portion of which receives a right gage 64, the central portion a somewhat lower spacer 65 and the right portion a lower right die 66 which is of less height than the gage 64 but higher than the spacer 65, these several members being secured in this groove by one or more fastening screws 67 arranged on the left wall of this holder.

Above the intermediate carrier is arranged a platen 68 which is secured to the lower end of the slide or plunger of the press so as to reciprocate vertically therewith and which supports on its underside two upper holders 69, 70 which carry means adapted to co-operate with the means on the lower holders for producing the hooks or flanges 25, 26 on the longitudinal edges of the blank preparatory to seaming them together. These upper holders are pivoted at their front ends

to the platen by screws 71 so that they can be turned horizontally into various angular positions relatively to each other, and the same may be retained in these positions by 5 adjusting screws 72 passing through the rear ends of these holders and one another pair of two curved rows of openings 73 in the rear part of the platen, each row being concentric with one of the pivot screws 71.

10 The upper left holder 69 is provided on its underside with a groove 74 in which is secured a punch 75 by means of clamping screws 76 on the adjacent part of the upper left holder which punch is adapted to co- 15 operate with the lower left die for producing the left upstanding hook or flange 25 on the blank. The upper right holder 70 is provided on its underside with a groove 761 the inner part of which receives a right 20 punch 77 and the outer part a spacer 78 of less height than the punch 77 and held therein by one or more clamping screws 79 arranged on the inner wall of said holder, said punch being adapted to co-operate with 25 the die of the lower right holder for producing the right hook or flange 26 on the blank.

Operation.

30 When the press is open the operator places a blank previously bent into tubular form around the horn and intermediate carrier and engages the left and right longitudinal edges of the blank with the left and 35 right gages 61, 64, as shown in Fig. 4. Upon now starting the press the upper platen first descends and causes its punches 75, 77 to engage the edge portions of the blank and bend them over the left and right dies 60, 40 66 and thus form the upstanding left flange or hook 25 and the downstanding hook or flange 26 on the right edge of the blank, as shown in Fig. 5.

After the platen has effected the initial 45 part of its downward movement and the blank is gripped between the tools of the upper and lower holders then the further downward movement of the platen causes the intermediate carrier to also descend until 50 the latter engages with the upper side of the horn, at which time the final pressure is exerted by the punches and dies on the blank for finishing the formation of the hooks or flanges, as shown in Fig. 5.

55 The press is now opened so that the intermediate carrier rises from the lower horn and the platen rises from the intermediate carrier, thereby releasing the blank on which the flanges have been formed on the longitudinal edges thereof. The operator now removes the flanged blank from the lower die holders and places the same around the horn with the hooks on its longitudinal edges loosely interlocked. In order to permit the 60 attendant to place the blank in the proper

position on the horn for subsequent operation of the flattening and seaming means, the operator first places the left edge of the blank in engagement with the left side of the gage 40 and then hooks the right flange 26 70 over the left flange 25. During the first part of the subsequent downward movement of the intermediate carrier the two hooks or flanges of the blank are bent backwardly so as to effect a greater hooking engagement of 75 the same, as shown in Fig. 6, but when the intermediate carrier has completed its downward movement the two hooks or flanges of the block are flattened by the upper and lower flattening blocks, the hooks are securely seamed together, and the seam projects laterally from the finished cone and is received in the groove on the underside of the upper flattening block, as shown in Fig. 7. While thus completing the seaming 80 operation on the cone the gage 40 recedes to the groove of the horn under the pressure of the upper flattening block, as shown in Fig. 7, but is again raised into its projecting position when the pressure of the upper 85 flattening block is removed.

It is thus possible to utilize one press for forming hooks on the blank and then interlocking and seaming them together by two successive operations of the press, thereby 90 reducing the amount of machinery for producing this work, also enabling the operator to perform this work easier and with greater expedition, and also reducing the investment for doing this class of work.

Moreover, this apparatus can be applied as an attachment to the standard forms of presses now in general use and thereby avoids the expense of installing special presses for this purpose.

I claim as my invention:

1. In a machine of the character described, the combination of two supports movable relatively to one another, a pair of tool holders mounted on each support and adapted to cooperate with the tool holders of the other pair, and means for changing the angularity of the holders of each pair relatively to one another.

2. In a machine of the character described, the combination of two supports movable relatively to one another, a pair of tool holders mounted on each support and adapted to co-operate with the tool holders of the other pair, and means for changing the angularity of the holders of each pair relatively to one another, consisting of a pivot connecting one end of each holder with its support, and a screw adapted to connect the other end of each holder with different parts of its support.

3. In a machine of the character described, the combination of two supports movable relatively to one another, a pair of tool holders mounted on each support and

adapted to co-operate with the tool holders of the other pair, and means for changing the angularity of the holders of each pair relatively to one another, two corresponding tools of said pairs of holders being adapted to produce a downstanding flange on one edge of a sheet metal blank and two other

corresponding tools of said pairs, being adapted to produce an upstanding flange on another edge of said sheet of metal. 10

In testimony whereof I affix my signature.

BROR J. LINDGREN.
